DESIGN FOR A JUICE EXTRACTOR

Henry J. Talge, Kansas City, Mo., assignor to John C. Hockery, Foster L. Talge, and Henry J. Talge, doing business as Rival Manufacturing Company, Kansas City, Mo.

Application November 24, 1944, Serial No. 116,519

Term of patent 14 years

(Cl. D89—1)

To all whom it may concern:

Be it known that I, Henry J. Talge, a citizen of the United States, residing at Kansas City, Jackson County, State of Missouri, have invented a new, original, and ornamental Design for a Juice Extractor, of which the following is a specification, reference being had to the accompanying drawing, forming part thereof, in which

Fig. 1 is a side elevational view of a juice extractor embodying the design,

Fig. 2 is a front view, and

Fig. 3 is a top plan view.

I claim:

The ornamental design for a juice extractor, substantially as shown.

HENRY J. TALGE.
